UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

UNDERFRAME.

1,078,309.

Specification of Letters Patent. Patented Nov. 11, 1913.

Application filed July 24, 1912. Serial No. 711,312.

To all whom it may concern:

Be it known that I, JOHN M. ROHLFING, residing at St. Louis, Missouri, and being a citizen of the United States, have invented 5 certain new and useful Improvements in Underframes, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown and 15 described, as it is obvious that various modifications thereof will occur to persons skilled in the art.

In said drawings: Figure 1 is a plan view of a fragment of a preferred embodiment 20 of my invention in connection with a portion of the underframe in advance of the cross-bearer. Fig. 2 is a side elevation of the structure illustrated in Fig. 1, with the bolster diaphragms removed. Fig. 3 is a 25 transverse sectional view through the draft sills and taken on a plane indicated by the line 3—3 of Fig. 2. Fig. 4 is a similar view taken on a plane indicated by the line 4—4 of Fig. 2. Fig. 5 is a view similar to Fig. 30 4, illustrating a fragmentary detail of a modified form of draft sills, and Fig. 6 is a front elevation of the bolster shown in Fig. 1, and showing the center sills in section.

One object of the invention is to provide a 35 plate girder end construction adapted to be used with an open truss girder center sill for railroad cars, the plate girder portion preferably extending from the end sill of the car through the bolsters, and as far toward 40 the middle of the car as the first cross-bearer, or other substantial part of the underframe, this plate girder being connected with the upper and lower chords of the truss girder.

Another object of the invention is to provide 45 a body bolster especially adapted for use in connection with the particular form of draft sills illustrated, which bolster is especially formed to coöperate therewith.

To maintain the standard distance be- 50 tween the inner faces of the draft sills, and at the same time to adapt them for attachment to standard or commercial size rolled sections of metal, I form the draft sills 1

of pressed metal, which draft sills are provided with offset portions 4 beyond the 55 bolsters to provide standard or regulation spacing of draft sills, and from the point of the offset rearwardly, the webs of the draft sills extending through the bolsters are spaced a less or greater distance apart, 60 though the top and bottom flanges are symmetrical throughout the length of the sills.

Disposed between the upper portions of the draft sills, and preferably flush with the top flanges and extending from a point 65 somewhat forwardly of the bolster to a corresponding position at the opposite end of the underframe, is a commercial size rolled channel section J, which section is riveted through its vertical depending flanges M to 70 the draft sills, or to the offset portions 4 thereof, which, as will be noted in Fig. 6, are deflected inwardly near their upper ends, for convenient attachment to the vertical flanges of said channel, which channel 75 is suitably connected to the filler R, forming part of the bolster hereinafter described.

The lower flange L of each of the draft sills is continuous from end to end, but is deflected upwardly, as shown at F, (see Fig. 80 2) where it passes over the outstanding lateral extensions I of the bolster filler hereinafter more fully described.

Secured between the draft sills 1 and bolsters, and extending longitudinally of the 85 center sills, is an inverted channel 2, which is secured through its depending flanges 8 to the webs of said draft sills, as shown more particularly in Figs. 2 and 4, but this channel may, if desired, be extended to the bottom bolster plate 3, as shown in Fig. 2, or it may be riveted, as shown in Fig. 5, and terminate in alinement with the raised portion F of the draft sill lower flange.

By reason of the peculiar formation of 95 the pressed draft sills, it is evident that the major portion of the web thereof may be continuous in a straight line from end to end and be spaced according to standard M. C. B. requirements, but owing to the fact 100 that it is difficult to secure rolled channel sections of a corresponding width, the inwardly bent or offset portions of the draft sills may be brought into contact with the depending flange of the commercial rolled 105 section, as illustrated, and secured thereto

to form a stiff buffering column to resist end shocks. By reason of the inward pressing of the metal of the draft sills at their upper portion, as shown in Fig. 3, there is a difference in the distance between the draft sills at top and bottom for a portion of their length, and likewise a difference in the distance between the upper portions of the draft sills near and between the bolsters and near the outer end portions of said sills, so that the outer portions of the draft sills may be spaced $12\frac{1}{2}$ " apart, to conform to M. C. B. requirements.

In order to fit a body bolster to the distorted draft sills, as above outlined, I form a continuous bolster comprising in effect three parts transversely considered; including a central filler R, which consists of two longitudinally spaced apart inverted T-shape flanged plates fastened by means of their flanges between and to the sills 1, conforming to the configuration of these sills and fastened to the under face of the channel section J. The outstanding lateral extensions I engage the inner side of the bottom flange of each of the side sills and extend outwardly therefrom some material distance to afford means for engaging the side bearings C at their ends.

Resting upon each of the extensions I and extending outwardly from the draft sills 1, is a pair of bolster diaphragms O, O and H, H, the diaphragms being arranged as shown in dotted lines in Fig. 1, so as to 35 form a horizontally disposed V, the outer ends of the bolsters on each side having their ends fastened together by rivets 9 passing through the webs of the diaphragms adjacent their outer ends.

It is to be understood that the filler R forms a continuation, and in effect a connecting member between each of the diaphragms O and H, so that the two diaphragms on each side and the two longitudinally spaced apart fillers R between the draft sills form in effect a relatively thin diamond shape bolster having flattened outer ends.

Each of the fillers R have outturned flanges G outlining the same, and each of the diaphragms have outturned flanges N, the diaphragms being fastened to the extensions I by means of rivets 10 passing through the outstanding flanges of the diaphragms and filler, and being fastened to the draft sills by means of rivets 11.

If desired, a top bolster plate 6 may extend across the channel section J, sills 1, and be fastened by means of rivets 13 to the outstanding flanges of the diaphragms O and H, this top cover plate conforming to the configuration of the top of the bolster, and, as shown in Fig. 1, preferably terminating short of the outer ends of the bolsters.

As is usual with constructions of this

character, a bottom bolster plate 3 may be fastened by means of rivets 14 to the bottom outstanding flanges of the filler, the transverse ends of which bolster plates may have upturned ends 15 overlapping the ends of the extension I and disposed between the ends of said extension and the downturned end 16 of the bottom diaphragm plates 17, which diaphragm plates extend outwardly over the side bearing C, and are fastened by means of rivets 18 to the lower outstanding flanges of the diaphragms O and H, bridging the spaces between the diaphragms on each side of the draft sills. By this construction it is seen that a relatively shallow bolster diaphragm may be used, the outstanding flanges assisting to resist any buckling of the diaphragms, and the bottom and top bolster plates forming respectively tension and compression members in a bolster in the form of a truss frame, parts of which frame are securely fastened to each other and to the peculiarly shaped draft sills, which construction adds transverse strength to the buffering column and materially assists to prevent the sills from spreading.

The draft sills 1 are pressed to the form indicated and are provided at their inner ends, that is the ends between the bolsters, with vertical flanges X, to which and to the web portions of said sills 1 are secured the cross-bearer Y, which may be, as shown in Figs. 1, 2 and 3, of channel form.

I claim—

1. The combination of draft sills positioned apart a distance to accommodate therebetween a regulation sized draft gear and a commercial channel section bridging a space between said sills less than the distance between other parts of said draft sills. 100

2. The combination of a pair of draft sills spaced apart a preset distance, a rolled commercial flanged section of preset width having a horizontal web portion which is disposed between and secured to said sills, 110 said sills being offset in horizontal lines to fit said section.

3. The combination of a pair of draft sills spaced apart a preset distance, a rolled commercial flanged section of preset width having a horizontal web portion which is disposed between said sills, said sills offset for a portion of their length to fit said section and being secured to its flanges. 115

4. The combination of draft sills spaced apart a regulation distance, a standard rolled section positioned between said sills, said section having horizontal web and vertical flanges, said sills being distorted to fit the flanges of said section. 120

5. The combination of draft sills spaced apart a regulation distance, a horizontally disposed member with vertical flanges po- 125

sitioned between said sills and contacting therewith, portions of the webs of each of said sills being displaced to fit said member.

6. The combination of a pair of draft 5 sills, a portion thereof spaced apart a regulation distance and a second portion thereof spaced a different distance apart, and a horizontally disposed flanged member fitting between said second portion with its vertical 10 flanges riveted to the sills.

7. The combination of a pair of draft sills, each having a vertical member, oppositely disposed portions of which members are parallel and spaced from each other a 15 regulation distance to accommodate a draft gear and another portion of which members are parallel and spaced from each other a slightly less distance to accommodate therebetween a flanged commercially 20 rolled section which has a horizontally disposed web portion, which web portion is of predetermined width differing from the said regulation spacing to accommodate draft gear.

25. 8. The combination of a pair of channel draft sills, a portion thereof spaced apart a regulation distance and another portion thereof vertically above the first portion being spaced apart a different distance to accommodate a horizontally disposed channel 30 bracing member therebetween.

9. The combination of a bolster, a pair of draft sills extending forwardly and rearwardly therefrom in a plurality of parallel 35 lines, the forward portion of said sills being positioned apart a regulation distance to form a definite space to accommodate a draft gear, and a bracing member comprising a horizontally disposed rolled channel extending 40 transversely to said bolster and fitting between said sills in rear of said draft gear space.

10. In an underframe, the combination comprising a horizontally disposed rolled 45 section with spaced vertical flanges and pressed metal sills secured to said flanges for a part of their length and spaced farther apart than said flanges for another part of their length.

50. 11. The combination comprising a horizontally disposed member, of uniform width, having spaced vertical flanges, and spaced draft sills having vertical webs secured to said flanges, the webs of said sills 55 being disposed in a plurality of vertical planes.

12. The combination comprising a horizontally disposed member, of uniform width, having spaced vertical flanges, and spaced draft sills of non-uniform depth secured thereto, the webs of said sills being deflected from perpendicular lines to contact with said flanges.

13. The combination comprising a hori-

zontally disposed member, of uniform width, 65 having spaced vertical flanges, and spaced pressed draft sills having vertical webs which are deflected transversely to contact with said flanges.

14. The combination comprising a horizontally disposed member, of uniform width, 70 having spaced vertical flanges, a bolster having a portion thereof extending between said vertical flanges, said bolster having extensions projecting beyond said member, and 75 spaced draft sills provided with vertical webs with deflected portions lapping said member and said bolster.

15. The combination comprising a horizontally disposed member, of uniform width, 80 having spaced vertical flanges, and pressed metal draft sills, the webs of which are deflected from vertical planes at their upper portions, lapping and secured to said flanges.

16. The combination comprising a horizontally disposed member, of uniform width, 85 having spaced vertical flanges, a bolster having a portion thereof extending between said flanges, and spaced draft sills with vertical webs having inwardly deflected upper portions lapping and secured to said flanges.

17. The combination comprising a commercially rolled member with horizontal web and depending flanges, of pressed draft sills of non-uniform depth secured to said 95 flanges for a portion of their length and spaced apart a different distance for another part of their length, and a bolster having a portion thereof secured to said horizontal web and underlying said sills. 100

18. The combination comprising a commercially rolled member with horizontal web and depending flanges, and a pair of spaced draft sills having vertical webs with inset portions secured to said flanges, and 105 other vertical portions spaced apart a greater distance than the distance between said flanges.

19. The combination comprising a commercially rolled member with horizontal 110 web and depending flanges, spaced draft sills having portions of their webs deflected inwardly and upwardly, and a bolster part extending between said flanges and below said upwardly deflected portion of the draft 115 sills.

20. The combination comprising a commercially rolled member with horizontal web and depending flanges, a bolster part secured to the web of said commercial member and extending transversely beyond the same, and pressed draft sills of channel form in cross section having web portions deflected from a perpendicular line to contact directly with said flanges, and having other 125 portions secured to portions of said bolster part which extend transversely beyond the flanges of said commercial section.

21. The combination comprising a commercially rolled member with horizontal web and depending flanges, a bolster part underlying said channel member and extending laterally therebeyond, and spaced draft sills overlying said bolster part, said sills being spaced apart different distances within their upper and lower portions at one side of said bolster.
- 10 22. In combination, parallel spaced draft sills having top and bottom flanges, said top flanges being parallel substantially throughout the length of the sills, and the webs of said sills being offset to contact with an interposed spacing member secured thereto at one portion and differently spaced at another portion to accommodate a standard draft gear.
- 15 23. In combination, a bolster and spaced draft sills which are parallel substantially throughout their length at each side of said

bolster and are deflected slightly transversely outwardly from or beyond said bolster to accommodate a standard draft gear, and a horizontally disposed channel interposed between said spaced draft sills. 25

24. In a car underframe comprising a bolster, a cross-bearer, spaced draft sills which extend substantially parallel from their outer ends to the cross-bearer, a commercially formed section with vertical flanges secured between the said sills at each side of the bolster, the outer end portions of said draft sills being spaced apart a greater distance than the width of said section. 30

35 In witness whereof I have hereunto set my hand in the presence of two witnesses.

JOHN M. ROHLFING.
